UNITED STATES PATENT OFFICE.

TAUBE DAVIS, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed August 12, 1926. Serial No. 18,703. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by an ornamental simulation of flower on the lapel and a tucked formation at the cen-

ter of the jumper or tunic with an ornamental strip and buttons extending across the tucked formation, the strip being associated with an encircling belt. The design is further distinguished by the jumper or tunic being of a contrasting color to the skirt.

The figure is a front view of a dress, showing my new design.

I claim:

The ornamental design for a dress, substantially as shown and described.

TAUBE DAVIS.
